W. C. WILLETS.
FOLDING BOX.
APPLICATION FILED NOV. 28, 1913.

1,144,804.

Patented June 29, 1915.

FIG. 1.

FIG. 3.

UNITED STATES PATENT OFFICE.

WILLIAM C. WILLETS, OF MINNEAPOLIS, MINNESOTA.

FOLDING BOX.

1,144,804.

Specification of Letters Patent. Patented June 29, 1915.

Application filed November 28, 1913. Serial No. 803,531.

To all whom it may concern:

Be it known that I, WILLIAM C. WILLETS, citizen of the United States, resident of Minneapolis, county of Hennepin, State of Minnesota, have invented certain new and useful Improvements in Folding Boxes, of which the following is a specification.

My invention relates to folding boxes and particularly to that type used as a receptacle for shipping purposes.

A further object is to provide a receptacle having a sealing means and adapted particularly for transporting articles, such as tobacco in various forms, and other articles of merchandise often stolen from a package in transit.

The invention consists generally in various constructions and combinations, all as hereinafter described and particularly pointed out in the claims.

In the accompanying drawings forming part of this specification, Figure 1 is a perspective view of a shipping box embodying my invention, Fig. 2 is a perspective view, looking directly into the box, showing a portion of the bottom of the box broken away and illustrating the preferred manner of sealing the bottom of the box, Fig. 3 is a detail sectional view, showing a modified construction in the form of the longitudinal flaps at the top and bottom of the box.

In the drawing, the box is shown composed of side panels 2, end panels 3, side flaps 4 and 5 at the bottom of the box, end flaps 6 at the bottom of the box, corresponding end flaps 7 at the top of the box and side flaps 8 and 9 at the top of the box. The box is made, preferably, from a single sheet of fiber-board or a similar material, creased and scored to form the panels and flaps above described, the ends of the blank being secured together, as at 10, by a suitable means to provide a rectangular receptacle in which the articles to be transported are placed. It is desirable to provide such a package with a sealing means which will positively prevent the opening of the top or bottom or any tampering with the sealing means without detection. I therefore provide the side panels with holes or perforations 11, preferably locating them near the upper and lower longitudinal edges of the panel and approximately in the middle thereof. Similar holes 12 are provided in the end panels. As shown, these holes may be at the junction of the end panels with the

end flaps 6 and 7, or, if preferred, they may be located intermediate to these points. The bottom side flap 5 is provided with holes 13 and 14 arranged preferably in pairs on each side of the middle portion of the flap and these holes register preferably with notches 15 and 16, also arranged in pairs in the edge of the flap 4. The upper, or cover flaps 8 and 9 have notches 15^a and 16^a which register with holes 13^a and 14^a in the flap 9 when the flaps are in their closed position. The lacing cord 17 is threaded through the holes and notches in the lower side flaps, and the ends threaded in and out of the holes 12 in the end flaps and through the holes and notches of the flaps 8 and 9, the loose ends of the cord being crossed in the middle of the box and one end being carried down and in and out of the side panel 2, across the flaps at the bottom, and in and out through the other side panel 2 to the top of the box, where the ends of the cord are secured together and sealed. The package is thereby closed and cannot possibly be opened without cutting the cord or damaging the box.

The notches are provided in two of the side flaps to facilitate the lacing of the cord on the box, as it can be slipped into the notches in less time than required to thread the cord through a hole in the flap. The box may be made of any suitable size or weight of material and in various ways the details of construction may be modified and still be within the scope of my invention.

In Fig. 3 I have shown a modified construction, which consists in providing top and bottom and side flaps 18 having edges 19 which are adapted to be folded into interlocking relation with one another, forming several thicknesses of the material along the middle line of the box at the top and bottom thereof. These folded edges are provided with openings 20 therein through which the lacing cord is passed in substantially the manner described with reference to the other figures of the drawing.

I claim as my invention:

1. A one piece folding box composed of a rectangular blank of flexible material, scored transversely and folded along said score lines to form the side and end walls of the box, the meeting ends of the blank being secured together, said blank having score lines running lengthwise thereof parallel with its longitudinal edges, and slits extending transversely thereof intersecting said

longitudinal score lines and in alinement with said transverse score lines, forming a series of flaps on each longitudinal edge of the box, said flaps being adapted to fold inwardly upon one another to close the top and bottom of the box, said side and end walls having openings therein and said side wall flaps having openings therein arranged in pairs, and a lacing cord passing through the openings in said side wall flaps at the bottom of the box and in and out through the openings in the end walls and in and out through the openings in the overlapping side wall flaps at the top of the box, and in and out through the openings in the side walls of the box, the ends of said cord being secured together.

2. A one-piece folding box having side and end panels and side and end flaps at the top and bottom, said side flaps being folded inwardly upon one another and upon said end flaps to close the top and bottom of the box, one of said side flaps having openings therein and the other adjacent side flap having notches to register with said openings, said side and end walls having openings therein, and a lacing cord passing through the openings in said side flaps and the notches in said side flaps and through the end walls and having its loose ends crossed and threaded through the openings in said side panels, the loose ends of said cord being secured together.

3. A folding one-piece box composed of flexible material having side and end panels and flaps formed thereon at the top and bottom of the box, said side and end panels having openings therein, the side flaps folding inwardly and lapping by one another, one of said side flaps at the top and bottom having notches therein arranged in pairs, the other side flap having openings adapted to register with said notches when said

flaps are folded to a closed position, and a flexible lacing means passing through the openings and notches in the bottom side flaps and through the openings in the end panels and the openings and notches in the top side flaps, the ends of said cord being crossed near the middle of the box and one loose end being carried down through the openings in one side panel and across the bottom and in and cut through the openings in the other side panel, and its loose end being secured to the other loose end, thereby sealing the contents of the box.

4. A one piece folding box composed of a rectangular blank of flexible material, scored transversely and folded along said score lines to form the side and end walls of the box, the meeting ends of the blank being secured together, said blank having score lines running lengthwise thereof parallel with its longitudinal edges, and slits extending transversely thereof intersecting said longitudinal score lines and in alinement with said transverse score lines, forming a series of flaps on each longitudinal edge of the box, said flaps being adapted to fold inwardly upon one another to close the top and bottom of the box, said side and end walls having holes therein and a pair of said longitudinal flaps having openings therein, the openings of one flap registering with the corresponding openings of the other flap, and a flexible lacing means threaded through said holes in said walls and through the openings in said flaps and extending around the sides and ends of the box, the loose ends of said lacing means being secured together.

In witness whereof, I have hereunto set my hand this 18th day of November 1913.

WILLIAM C. WILLETS.
